UNITED STATES PATENT OFFICE.

RUDOLF GEIPERT, OF BERLIN, GERMANY, ASSIGNOR TO DESSAUER VERTIKAL OFEN GESELLSCHAFT, OF BERLIN, GERMANY, A CORPORATION OF GERMANY.

METHOD OF HEATING COKE-OVENS.

1,281,775.

Specification of Letters Patent. Patented Oct. 15, 1918.

Application filed February 24, 1915. Serial No. 10,387.

To all whom it may concern:

Be it known that I, RUDOLF GEIPERT, a subject of the Emperor of Germany, and resident of Berlin, Germany, have invented 5 certain new and useful Improvements in Methods of Heating Coke-Ovens, of which the following is a specification.

In United States Letters Patent No. 1,208,134 issued to applicant December 12, 1916, applicant has described an invention 10 which relates generally to the construction and mode of operation of coke ovens with closed retorts externally heated and which refers particularly to a process of heating 15 coke ovens with either producer gas, or illuminating gas such as is obtained for instance, in the coking of coal, a particular feature of this process being the generation of a limited quantity of producer gas during the period of burning illuminating gas 20 in order to keep the fuel bed of the gas producer hot enough to permit, on a moment's notice, the heating of the coking oven exclusively by producer gas instead of 25 by illuminating gas.

In the present application is described a further improvement on this process by which considerable advantages are effected by transforming the illuminant parts of the 30 illuminating gas into gases burning without flame by passing the same through the incandescent zone of the gas producer and simultaneously burning the same together with the quantities of producer gas generated, in the manner described below.

According to the present invention the illuminating gas used in the heating of the retorts is either burned before its entrance 40 into the producer or it is burned in the producer either totally or partly so that its illuminating parts are destroyed. The hot gaseous products resulting from the combustion of the illuminating gas, chiefly carbon dioxide gas and water vapor, travel 45 through the generator and keep its fuel bed in an incandescent state, being, however, at the same time transformed into carbon monoxide and hydrogen gas, which latter are conducted into the furnace proper to be 50 burned there for heating the retorts.

The present invention affords the great convenience that only small quantities of solid fuel are to be burned by air in the

producer in order to keep the same at the proper incandescent point, and it even permits the shutting off of the air entirely without discontinuing the combustion of the coke.

The process will be fully understood by referring to the accompanying drawing 60 which illustrates in a vertical section one way of constructing both a coking oven and a gas producer suitable for the operation of the invention.

The gas producer *a* is connected by a cross-channel *b* and lateral channels *c*, branching off from cross-channel *b*, with the furnace chamber *d* in which the retorts *e* are located. The air for the combustion of the gas is admitted by means of the channels *f* 65 opening into the upper part of the lateral channels *c*. In order to regulate the volume of air necessary for the production of producer gas a plate valve *g* is provided in the lower door *h* of the gas producer. A main pipe *i* for illuminating gas, provided with 70 shut off valves *k*, is connected to horizontal channels *m* leading through the wall of the generator where their exits *n* are in juxtaposition to the exits *p* of channels *q* regulated by plates *r* and serving for the admission of air. Below the channels *m* and *q* is the grate *o* of the gas producer.

While the oven is being heated by producer gas the valve *k* of the main gas pipe *i* 85 and the plates *r* of the channels *q* are closed, whereas the plate *g*, admitting and regulating the entrance of air to the producer, is rather wide open so that all the producer gas necessary for operating the coking oven may 90 be generated.

During the period of burning illuminating gas the plate *g* is opened only very little if opened at all, so that at this point only very little air, or none respectively may 95 enter. The illuminating gas required for the heating of the coking oven flows through the channels *m* into the producer and is mixed at the exits *n* with the air leaving channels *q* at the exits *p*, the volume of the air being regulated by the plate *r*. The gas mixture thus obtained is burned either before or after it enters the gas producer; the products of the combustion, transformed into carbon monoxide and hydrogen while passing through the incandescent fuel bed of the 100

105

gas producer, travel through the channels *b* and *c*, to be mixed with air flowing through channels *f*, to finally be burned in the furnace chamber *d*.

5 The process described in the present application is, like the process described in United States Letters Patent No. 1,208,134 issued to applicant December 12, 1916, suitable not only in case frequent changes in the manner of heating the coking ovens have to be resorted to, but also offers great advantages in case the same are to be heated with illuminating gas either for long intervals or continuously, because rendering the gas non-luminous is then always desirable and often becomes a direct necessity. Also in the cases where no particular stress is laid upon the application of non-luminous gases just as well as in cases where non-luminous gases 15 are used for heating the coking oven, a most desirable and important advantage is obtained inasmuch as because of the hot fuel bed the producer explosions are avoided and a remarkably great safety in the operation 20 of the process is obtained.

The illuminating gas coming in consideration for the present invention is for instance derived from bituminous coal, lignite, peat and the like substances. The gas could also 30 be freed from its luminous parts by being washed with oils or other suitable like substances.

As in the process disclosed in said Patent No. 1,208,134 which may be carried out in 35 plants where the gas-producers and coking ovens are separated from each other by considerable distances, so the process described in the present application may be carried out in coking ovens which do not 40 adjoin the gas producer; but where, for instance, a large central station of gas producers is established somewhat remote from the coking ovens proper.

What I claim and desire to secure by Letters Patent is: 45

1. In methods of heating coke ovens and the like by alternately burning producer-gas and illuminating gas in the same, the method of treating the illuminating gas consisting in burning a part of the illuminating gas, 50 passing both its combustion products and the other part of the illuminating gas through a column of incandescent fuel and burning the combustible gases thus obtained in the coke oven. 55

2. In methods of heating coke ovens and the like by alternately burning producer gas and illuminating gas in the same, the method of treating the illuminating gas consisting in maintaining a column of fuel in incandescent 60 state by the heat generated by the combustion of illuminating gas, passing the products of the combustion of the gases through said incandescent column and burning the combustible gases thereby obtained in the 65 coke oven.

3. In methods of heating coke ovens and the like by alternately burning producer gas and illuminating gas in the same, the method of treating the illuminating gas consisting in 70 burning illuminating gas within a gas producer containing a column of incandescent fuel, maintaining said column of fuel in incandescent state by the heat generated by the burning illuminating gas, passing the 75 products of combustion through the incandescent column and burning the combustible gases thereby obtained in the coke oven.

In testimony whereof I have signed this specification in the presence of two subscribing witnesses.

RUDOLF GEIPERT.
